UNITED STATES PATENT OFFICE.

WILLIAM C. BUCKLEY, OF CROOKSTON, MINNESOTA.

TOOTHBRUSH HOLDER.

Application filed July 2, 1924. Serial No. 723,828.

To all whom it may concern:

Be it known that I, WILLIAM C. BUCKLEY, a citizen of the United States, residing at Crookston, in the county of Polk and State 5 of Minnesota, have invented certain new and useful Improvements in a Toothbrush Holder, of which the following is a specification.

This invention relates to an improved holder or receptacle for tooth-brushes, the 10 primary object of which is to provide a device of this character which will enclose the bristles of the brush and retain same in a sanitary condition.

A further object of the invention is to 15 provide a device of this character which will support a plurality of brushes and will keep the same properly spaced apart.

A still further object of the invention is the provision of a holder of this character 20 having means for permitting the circulation of air through the same for drying the brushes.

A still further object of the invention is the provision of a device of this character 25 which is of simple construction, durable, and efficient for this purpose.

Other objects and advantages of this invention will be apparent during the course of the following description.

30 In the accompanying drawing forming a part of this specification and in which like numerals are employed to designate like parts throughout the same:

Figure 1 is a front elevation of the invention showing brushes placed therein,

Figure 2 is a side elevation of the same,

Figure 3 is a vertical sectional view taken on the line 3—3 of Figure 1,

Figure 4 is an enlarged plan view of my 40 improved holder, and

Figure 5 is a transverse sectional view taken on the line 5—5 of Figure 4.

In the drawing, wherein for the purpose of illustration is shown the preferred embodiment of my invention, the numeral 10 generally designates the casing or holder which is substantially rectangular in shape and provided with rectangular openings 11 cut from the lower portion of the sides

50 and similar but smaller openings 12 cut from the upper portions thereof. The back, sides and end walls of the casing 10 may be constructed of some light metal, celluloid or any desirable material, a rectangular plate 13 of the same material being positioned at the upper extremity of the cas-

ing front. The greater portion of the front casing section is preferably covered by a strip of transparent material 14, this strip may be constructed of mica, glass or the like. 60 It is also to be understood that the device may be of any desired shape in order to retain any desirable number of brushes, the size of the container varying according to kind and number of brushes it is desired to 65 enclose therein.

The upper portion of the casing 10 comprises a top strip or plate 15 extending from the back a comparatively slight distance across the upper portion of the container and having formed therein a pair of longitudinal openings 16 adapted to permit extension of the brush handle through the upper portion of the container. A lid or cover 17 is hingedly mounted at the upper portion of the container opposite the extension strip 15, this lid being connected to the front plate 13 by means of a pivot rod 18 extending through suitable hinge extensions 19 formed in the lid and upper portion of the front plate 13. It is obvious that this lid will be permitted to swing upwardly and downwardly about the pivot rod to permit insertion of the tooth-brush. 70 As it is desirable to normally retain the lid 75 in a horizontal position I provide a pair of coil springs 20 and 21 to accomplish this purpose.

The coil spring 20 is wound about one portion of the pivot rod 18 and has one extremity extending over the lid member 17, the other end extending on the outer side of the plate 13, thereby having a tendency to force the lid in a downward position as shown by the numeral 22 in Figure 3. The 80 second coil spring 21 is wound about the opposite section of the pivot rod and has one extremity engaging the lower portion of the lid 17 while the opposite end thereof extends downwardly within the casing, this 85 spring exerting a tension against the lid 17 and tending to force the same upwardly as shown in dotted lines at 23. It is necessary that these springs be of uniform strength in order to normally retain the lid 100 in the horizontal position although capable of being readily swung up or down by contact of the tooth-brush.

In order to retain the brushes separated for sanitary purposes I provide a partition 110 plate 24 having a longitudinal opening 25 cut from the central portion thereof, this

partition being mounted transversely across the lower portion of the casing to form separate stalls for the brushes.

As it is customary to hang the brush container upon a wall I provide a back plate 26 secured to the upper portion of the casing back having formed on the upper central portion an ear 27 having a suitable opening formed therein as shown at 28 for the insertion of a nail or retaining brad.

In use, the tooth-brush owner may readily withdraw the same from the casing by grasping the upper extremity of the handle and drawing same upwardly, the brush head and bristles forcing the upper lid 17 to open position and permitting withdrawal of the same. When returning the brush the lid is readily forced downwardly in a like manner and the brush deposited in its proper compartment. This device obviously furnishes a container which is readily accessible and extremely sanitary, providing separate compartments for each tooth brush deposited therein and also providing means for readily drying the bristles. The transparent front wall enables the owner to readily identify his brush and prevent the use of another's brush, it being intended that the brush be deposited in the same compartment at all times.

It is to be understood that the form of my

invention herewith shown and described is to be taken as the preferred example of the same, and that various changes as to the shape, size, and arrangement of parts may be resorted to without departing from the spirit of the invention or the scope of the subjoined claim.

Having thus described my invention, I claim:

A tooth-brush holder comprising a relatively long body having a partition wall located therein and extending from the bottom wall of the body to a line spaced from the upper end of the body and dividing the interior of the lower portion of the body into compartments, the side walls of the body and the partition wall having relatively long openings which register with each other transversely of the body, said openings being located in the vicinity of the lower end of the body, the side walls of the body being provided at points spaced above the upper edges of the said openings with relatively short openings, the said relatively short openings being located above the upper edge of the partition wall and a hinged closure for the upper end of the body.

In testimony whereof, I have affixed my signature.

WILLIAM C. BUCKLEY.
